(57) **CLAIM**

The ornamental design for a surface configuration of a headlight for a vehicle, as shown and described.

DESCRIPTION

This application is related to the following co-pending application, of the inventor: application Ser. No. 29/170,335, entitled “Surface Configuration of a Vehicle, Toy and/or Other Replicas”.

FIG. 1 is a front view of a first embodiment of a surface configuration of a headlight for a vehicle according to my novel design;

FIG. 2 is a perspective view of the first embodiment of the surface configuration of a headlight for a vehicle according to my novel design;

FIG. 3 is a front view of a second embodiment of the surface configuration of a headlight for a vehicle according to my novel design; and,

FIG. 4 is a perspective view of the second embodiment of the surface configuration of a headlight for a vehicle according to my novel design.

The dash lines included depict environment and are not part of the claimed design.
